CLAIM

The ornamental design for a battery charger and stand for a cordless telephone and associated wireless communications headset, as shown and described.

DESCRIPTION

FIG. 1 is an upper right front perspective view of a battery charger and stand for cordless telephone and associated wireless communications headset showing our new design;

FIG. 2 is an upper left front perspective view thereof;

FIG. 3 is a front elevation view thereof;

FIG. 4 is a back elevation view thereof;

FIG. 5 is a right side elevation view thereof;

FIG. 6 is a left side elevation view thereof;

FIG. 7 is a top plan view thereof; and,

FIG. 8 is a bottom plan view thereof.
